UNITED STATES PATENT OFFICE.

FRANCIS O. RICHEY, OF ELYRIA, OHIO, ASSIGNOR TO THE DEAN ELECTRIC COMPANY,
OF ELYRIA, OHIO, A CORPORATION OF OHIO.

TELEPHONE-RECEIVER SHELL.

1,033,938.

Specification of Letters Patent. Patented July 30, 1912.

Application filed September 27, 1909. Serial No. 519,793.

To all whom it may concern:

Be it known that I, FRANCIS O. RICHEY, a citizen of the United States, residing at Elyria, in the county of Lorain and State of Ohio, have invented certain new and useful Improvements in Telephone-Receiver Shells; and I do hereby declare the following to be a full, clear, and exact description of the invention, such as will enable others skilled in the art to which it appertains to make and use the same.

My invention relates to telephone receivers, and has for its object the construction of a receiver shell of metal which shall accomplish all the purposes heretofore secured in connection with shells for such instruments and having the additional advantages of lightness, durability, improved appearance and cheapness.

20 Receiver shells have commonly been made heretofore of insulating material of one form or another which, generally speaking, is very brittle in nature and therefore easily broken. To avoid this difficulty, the shells 25 have usually been constructed of considerable thickness with the result that they are both clumsy and heavy. By my invention I construct these shells of thin sheet metal, folding them over at the edges where the 30 parts are to be joined, causing the folded portions to cohere with the main portions and cutting threads in the double thickness of material thus furnished.

If preferred, a cap of insulating material 35 may be used in connection with the metal shell instead of the metallic cap which is referred to.

In constructing my improved receiver shell, I make use preferably of forming dies 40 to form suitable sheet metal into the desired conformation. In order to be readily manipulated so as to assume the form required, the sheet metal used must be preferably relatively thin. This thin material, however, is not adapted to be threaded, since the threads would be so fine necessarily as to be 45 of no use. Furthermore, the threaded portion would not possess sufficient rigidity to readily engage the coöperating threaded member. By my invention I eliminate this difficulty by folding the metal over and cutting the threads in the portion rendered 50 doubly thick this way. The threads may be cut through one portion into the other without danger of the spiral part left in the

upper portion shifting, as the parts are caused to cohere. The under part of the fold furnishes the backing or support when the threads are cut. I realize the advantage of lightness by this expedient, for, if the material were made thick enough to hold the threads, the shell resulting therefrom would be so heavy as to practically prohibit its use.

A further advantage secured by my improved construction is to be found in the case in which the main portion or both the shell proper and the cap are formed, for the sake of cheapness, of thin sheet metal.

In connection with the use of sheet steel for forming the main portion of the shell 70 proper and the cap, I employ a protecting varnish or coating, as for example, enamel or japan, to thoroughly protect the steel from the contact of moisture.

My invention will be best understood by 75 reference to the following description when taken in connection with the accompanying illustration showing one specific embodiment thereof, while its scope will be more particularly pointed out in the appended 80 claims.

In the drawing, Figure 1 is an elevation of the cap and a fragment of the body portion, each cut away to show the threads in section. Fig. 2 shows the same view with 85 the cap united to the body portion.

Referring to the drawing and to the embodiment of my invention shown therein, at 1 I illustrate the ear end of the body portion carrying a shoulder 7. The metal of the shell is folded over at this shoulder as shown at 4. The folded portion is fastened to the main part by a cementing material or by compression, or other means, which will cause the contacting surfaces of the 90 body and fold to stick together. I then cut threads 3 on the threaded portion. These threads may extend through the sheet metal of the fold into that of the body. The metal of the body portion or of the lower 100 fold, as the case may be, furnishes a backing for the operation of cutting the threads, and by its cohesion to the parts of the other fold left after the threads are cut, prevents their shifting. At 2 I show a cap having a 105 shoulder 8 folded at 5 and having the threads 6 cut into it much the same way as described for the body portion.

While I have shown my invention in this particular form, I contemplate folding the 110

portions under or over, as I shall see fit, and cutting the threads on the inside or outside, as may be most expedient. It will also be obvious to those skilled in the art, that numerous and extensive departures from the form and the details of the apparatus herein shown may be made without departing from the spirit of this invention, the same being here shown solely for the purpose of clearly illustrating one specific embodiment thereof.

I claim:

1. In a telephone receiver shell, the combination of a body portion folded over at an edge, threads on said folded part and the body portion for securing them together, a cap, and means to attach said cap to said body at said folded edge.
2. In a telephone receiver shell, a body portion, a cap portion, one of said portions having its edge folded over and secured to said portion at the contacting surfaces, and thread fastening means supported by said folding portion whereby said cap is secured to said body portion.
3. In a telephone receiver shell, a body portion having its edge folded over and secured to the main part at the contacting surfaces of the folded part and the body part, threads cut in said body portion at the folds, said threads extending through the folded part into the main part, a cap having a folded edge, threads cut in said cap at the

folded edge adapted to coöperate with the threads of the body portion to attach said cap to said body portion.

4. In a telephone receiver shell, a body portion having its edge folded over against the main portion and secured thereto, threads extending through the folded portion into the main portion, a cap having threads cut therein adapted to engage the threads cut in the body portion to secure the cap on the main portion.

5. In a telephone receiver shell, a body portion having an edge folded over, extending substantially parallel with the main portion and secured thereto, threads cut through the folded portion into the main portion and a threaded cap engaging the threads to secure said cap and body portion together.

6. In a telephone receiver shell, a body portion having an edge folded over against the body portion and secured thereto threads cut through the folded part into the main portion and a threaded cap adapted to engage the threads on the main portion to secure the cap and the shell together.

In testimony whereof I affix my signature in presence of two witnesses.

FRANCIS O. RICHEY.
